UNITED STATES PATENT OFFICE.

HENRY CLIFFORD EGERTON, OF PASSAIC, NEW JERSEY, ASSIGNOR TO WESTERN ELECTRIC COMPANY, OF NEW YORK, N. Y., A CORPORATION OF ILLINOIS.

TELEPHONIC APPARATUS.

1,140,366.

Specification of Letters Patent. Patented May 25, 1915.

Application filed January 22, 1914. Serial No. 813,662.

To all whom it may concern:

Be it known that I, HENRY CLIFFORD EGERTON, a citizen of the United States, residing at Passaic, in the county of Passaic and State of New Jersey, have invented a certain new and useful Improvement in Telephonic Apparatus, of which the following is a full, clear, concise, and exact description.

10 This invention relates to telephone receivers and more particularly to a telephone receiver for amplifying the received voice currents.

15 The object of this invention is to provide a new and improved device of this character of few and simple parts, efficient in operation and easily maintained.

20 In accordance with this invention there is combined in a single structure two independently operable receiver structures having certain of their parts in common. Both structures are operated with a single permanent magnet. Possibilities of cross talk or interference between the two receivers is 25 eliminated by reason of a differential magnetic circuit. The device is rendered compact in form and easily assembled by the details of construction and means provided for the mounting of the parts.

30 In the drawings illustrating this invention,—Figure 1 is a plan view of the device with the cover removed and parts in section; Fig. 2 is a sectional view taken upon line 2—2 of Fig. 1; Fig. 3 is a perspective of the 35 magnet system of the device; Fig. 4 is a detail sectional view taken upon line 4—4 of Fig. 1; and Fig. 5 is a diagram of the magnetic circuit of the device.

As shown in the drawings, there is provided a frame member comprising a generally rectangular portion 5, having an extension 6 thereon opening into the rectangular portion 5 and having formed therein seats 7 for diaphragms 8, 8. The rectangular portion 5 is divided into two compartments 9, 9 by means of a partition wall 10 located centrally of said rectangular portion. Located in each of these compartments 9, 9 is an electromagnet comprising two coils 12, 12, and one arm 13 of a horseshoe magnet 14, the main portion of which is located in the frame extension 6. The coils 12, 12 of each electromagnet are supported upon extensions 15, 15, of a magnetic

yoke 16 which is rigidly secured to an enlarged portion 17 of the partition wall 10 of the rectangular frame portion 5.

The mechanical features of the receivers are the same and a description of one will suffice for both.

Referring particularly to Figs. 2, 3 and 4 it will be noted that the coils 12, 12 of the electromagnet are of the solenoid form, each being provided with an adjustable core 20. Located between each pair of coils 12, 12 is a supporting block 21 from which is supported a lever arm 22. Each lever arm has knife edge extensions 23, 23 engaging notches in the supporting block 21 and is maintained in position by means of a suspending wire 24 secured to said block 21 and passing through an opening 25 in a projection 26 carried by said lever arm. Secured to said lever arm 22 at equal distances upon each side of the extensions 23, 23 are plunger members 28, 28 of magnetic material which project into the solenoids 12, 12 and are attracted and repelled by the magnetism set up in said coils by the energization thereof. The lever arm 22 extends into the frame extension 6 and is secured to the diaphragm 8. Secured to the frame extension 6 is a supporting member 30 for a sound deflector, having two angularly disposed openings 31, 31, one opening directly above the central portion of a diaphragm 8 and the two openings verging into one near the outer end of the support to which a sound deflector or horn may be attached. Top and bottom cover plates 35 and 36 are secured to the frame by means of screws 37, 37. Wires may be led into terminals 38, 38 within the casing through insulating bushings 39, 39 secured therein.

Referring now to Fig. 5 in which the magnet system is shown diagrammatically, let 40 and 41 designate the line wires connecting with the electromagnets of one receiver and 42 and 43 the line wires connecting with the electromagnets of the other receiver. Assuming that a conversation is being carried on over the line wires 40 and 41, this will cause an unbalance in the magnetic circuit of the solenoids associated with these line wires, but not in that associated with the other line wires in spite of the fact that the permanent magnet 14 and the yoke 16 are common to the two receivers. This is

- due to the fact that the unbalance of a particular structure is localized since the increase or decrease of the magnetic lines of force will pass through the yoke portion 16 and be equally divided between the cores of the electromagnets which are not receiving energizing current. As illustrative, assume that there is a magnetic flux through the magnetic circuit including the polarized magnet 14, the plungers 28, 28, the cores 20, 20 and the yoke 16 and its extensions 15, 15 of a strength say of sixteen units. This will under ordinary circumstances divide equally between the cores and plungers of the electromagnets so that the system will be in a state of equilibrium. If, however, there is talking current over the wires 40 and 41, it will cause an unbalance in the magnetic circuit of the solenoids associated therewith, causing say twelve units to flow through the core and plunger of one solenoid and only four units through the core and plunger of the other solenoid; thus causing the movement of the lever arm controlled thereby. Due, however, to the fact that the return path for these lines of force is through the yoke 16, which is common to the two electromagnets, they must all flow therethrough and will divide equally between the cores and plungers of the other solenoids without affecting the lever arm controlled thereby. This structure permits of the independent operation of two receivers with a single permanent magnet without interference or cross-talk between them. This not only reduces the cost of the equipment for installations of this type but simplifies the construction and makes easier the maintenance of the apparatus.
40. What I claim is:
1. Two independently operable telephone receivers having a common differential magnetic circuit.
  2. Two independently operable telephone receivers having in common a permanent magnet and a magnetic return path.
  3. Two independently operable telephonic receivers having in common a permanent magnet, a magnetic return path and a sound deflector.
  4. In a telephonic device, a pair of diaphragms, independently operable electromagnets controlling the operation of said diaphragms, and means forming a differential magnetic circuit for said electromagnets.
5. In a telephonic device, a pair of diaphragms, independently operable electromagnets controlling the operation of said diaphragms, and a magnetic circuit common to said independently operable electromagnets.
6. In a telephonic device, a pair of diaphragms, independently operable electromagnets controlling the operation of said diaphragms, a permanent magnet common to both said electromagnets, and a yoke also common to both said electromagnets.
7. In a telephonic device, a pair of diaphragms, independently operable electromagnets controlling the operation of said diaphragms, a permanent magnet having one pole associated with each of said electromagnets, and a yoke of magnetic material forming a common return magnetic path for both said electromagnets.
8. In a telephonic device, a pair of diaphragms, an electromagnet operatively connected with each of said diaphragms, a frame for said electromagnets, a partition dividing said frame into compartments, each inclosing an electromagnet, a permanent magnet having one pole in each of said compartments, and a yoke for said electromagnets secured to said partition.
9. In a telephonic device, a pair of diaphragms, an electromagnet operatively connected with each of said diaphragms, a supporting frame comprising a rectangular frame member having an extension thereon, said extension opening into said rectangular portion and being provided with seats for said diaphragms, a partition dividing said rectangular portion into two compartments in which are located said electromagnets, a permanent magnet having one leg located in each of said compartments and its main portion in said extension, and a connecting yoke supporting said electromagnets secured to said partition.
- In witness whereof, I hereunto subscribe my name this 20th day of January A. D., 1914.
- HENRY CLIFFORD EGERTON.
